CLAIM

The ornamental design for an electrophotographical duplicator, as shown and described.

DESCRIPTION

FIG. 1 is a perspective view of the electrophotographical duplicator showing my new design;

FIG. 2 is a front elevational view thereof with the input and output trays removed;

FIG. 3 is a rear elevational view thereof with the input and output trays removed;

FIG. 4 is a right side elevational view thereof with the input tray removed;

FIG. 5 is a left side elevational view thereof with the output tray removed;

FIG. 6 is a plan view thereof with the input and output trays removed; and

FIG. 7 is a bottom view thereof with the input and output trays removed.
